(57) CLAIM

The ornamental design for a sand sifter, as shown and described.

DESCRIPTION

1. Sand sifter
- 1.1 : Perspective
- 1.2 : Perspective
- 1.3 : Top
- 1.4 : Bottom
- 1.5 : Left
- 1.6 : Back

Sand sifter for use with a cleaning bucket; front view is omitted because it is identical with the back view; right side view is omitted because it is identical with the left side view.
